[57] CLAIM

The ornamental design for a combination ice chest and entertainment apparatus, as shown and described.

DESCRIPTION

FIG. 1 is a perspective view of a combination ice chest and entertainment apparatus showing our new design, one lid shown in an open position;

FIG. 2 is a top plan view thereof in a closed position;

FIG. 3 is a front elevation view thereof;

FIG. 4 is a rear elevation view thereof;

FIG. 5 is a bottom plan view thereof; and,

FIG. 6 is a right side elevation view thereof, the opposite side being a mirror image.
